DESIGN FOR A LAMP FOR COOKING RANGES

David L. Edelmuth, Shaker Heights, Ohio, assignor to The Cleveland Co-Operative Stove Company, Cleveland, Ohio, a corporation of Ohio

Application December 20, 1940, Serial No. 97,488

Term of patent 3½ years

To all whom it may concern:

Be it known that I, David L. Edelmuth, a citizen of the United States, residing at Shaker Heights, in the county of Cuyahoga and State of Ohio, have invented a new, original, and ornamental Design for a Lamp for Cooking Ranges, of which the following is a specification, reference being had to the accompanying drawing, forming a part thereof.

Fig. 1 is a front elevational view of a lamp for cooking ranges showing my new design, Fig. 2 is a side elevational view thereof, and Fig. 3 is a fragmentary sectional view thereof as indicated by the line 3—3 on Fig. 1.

I claim:

The ornamental design for a lamp for cooking ranges, substantially as shown.

DAVID L. EDELMUTH.
